SCALDER

Raymond L. Haynie, Reedville, Va.

Application December 27, 1940, Serial No. 371,967

5 Claims. (Cl. 146—47)

This invention pertains to scalders; and more particularly, to the type of scalders used in canneries for scalding tomatoes, and like material, to facilitate the easy peeling thereof, and this application is directed to the same disclosure and claims the same subject matter as my application Serial Number 324,207, filed March 15, 1940, allowed December 4, 1940, and subsequently forfeited.

Injecting the heating steam into the liquid causes a turbulation which would be injurious to the material being scalded if the steam injection were made in the compartment containing the material. I, therefore, provide one or more auxiliary compartments in which I inject steam which heats the scalding liquid, and I circulate the heated liquid from the auxiliary compartments through the material confining compartment back into the auxiliary compartments. The passages from the auxiliary compartments into the material compartment and from the material compartment back into the auxiliary compartments are of such size that the speed of circulation of the liquid is governed, the circulation inducing steam inlet and baffle in the material compartment being adjustable to determine the speed of flow.

In my prior Patent No. 2,111,285, of March 15, 1938, I disclose a scalding machine embodying a nozzle for injecting steam into the scalding liquid to induce circulation of the liquid, and a baffle plate to direct the circulation. My present invention is an improvement of the machine in the prior patent.

I have noted that ripe tomatoes will sink, and unripe tomatoes will float. Tomatoes of intermediate ripeness will remain suspended between the surface of the liquid and the bottom. Furthermore, ripe tomatoes require a less time in the scalding liquid for the heat penetration required to release the peelings.

I therefore, provide a container for the material with a minimum horizontal area at the lowest depth, the successive horizontal areas constantly increasing progressively towards the surface, by disposing the tomato conveyor at an angle to the supply chute. The circulation of the scalding liquid through the material compartment is timed in accordance with the speed of the conveyor to permit the unripe tomatoes to remain in the scalding liquid a longer time than the ripe ones and to vary the time the tomatoes are treated in the liquid in accordance with their ripeness.

As a further control, I provide means to adjust

the depth of the scalding liquid relative to the depth of the material in the compartment to regulate the time of treatment of the material being scalded.

5 Thus, a scalding machine made in accordance with my invention will scald the tomatoes so that all of them receive sufficient treatment to release the peelings, the degree of treatment being in accordance with the degree of ripeness. All tomatoes of a given batch receive the amount of scalding necessary to release the peelings, regardless of the degree of ripeness of the several tomatoes in the batch. The scalding treatment is regulated to the minimum required to accomplish the purpose of releasing the peelings and enables their ready removal. The penetration is thus maintained at a minimum and confines the cooking of the tomato to the surface.

I also provide means to chill the tomatoes 10 after they have left the scalding compartment and while they are still on the conveyor. This sudden change from a scalding temperature to the temperature of cold water causes the peelings of the tomatoes to crack, and enables them 15 to be removed more readily.

Having thus stated the nature of my invention in general terms, attention is now directed to the drawings, in which:

20 Figure 1 is a side elevation of the machine; Figure 2 is a cross-sectional elevation taken on line 2—2 of Figure 3;

25 Figure 3 is a plan view; Figure 4 is a cross-sectional elevation taken along the line 4—4 of Figure 2;

30 Figure 5 is a cross-sectional elevation taken on line 5—5 of Figure 2; Figure 6 is a cross-sectional elevation taken on line 6—6 of Figure 2; and

35 Figure 7 is a detailed view of the chilling means disclosed in Figure 2.

40 Viewing Figure 1, there is noted the vat-like container 11 mounted on the supporting uprights 12. The container 11 is adapted to be filled with water or some other suitable medium for scalding the tomatoes or other fruit to be treated by the machine.

45 Within the container, as viewed in Figure 2, there is the conveyor 14 which functions to transport the material through the scalding liquid 50 during its treatment and out of the liquid to a deposit station indicated generally at 15. The conveyor comprises an endless movable bed 16 preferably consisting of chain-like fabric to provide perforations, indicated clearly in Figure 3, through which perforations the scalding liquid

can travel freely. Transverse cleats 17 are mounted on the conveyor 15 to engage the material being scalded and carry it with the conveyor bed.

The conveyor is mounted on the shafts 18 and 19, the shaft 18 being driven through a sprocket and chain 20 and 21 or through other suitable driving mechanism from a source of power not shown. The shaft 18 is preferably mounted in fixed bearings. The shaft 19 in the preferred application of the invention, is mounted in movable bearings indicated at 22, Figure 1, to permit the shaft 19 to be adjusted to apply a greater or lesser tension to the conveyor bed 16.

As noted in Figure 2, the conveyor 14 is disposed longitudinally of the container 11 and extends from a position near the lower lefthand corner of the container to a position 15 outside of the container and beyond it. The conveyor bed thus is disposed diagonally lengthwise of the container.

Tomatoes, or other material to be scalded, are deposited in the supply chute 23 which comprises the sides 24 and the bottom 25. The bottom 25 consists of a plurality of longitudinal ribs 26 disposed in parallel relationship and held in position by the end frame members 27 and 28. The ribs 26 provide sufficient open space between them to permit the ready flow of the water therethrough.

The bottom 25 is disposed at an angle with the bed 16 to provide a horizontal area for the material which is smallest at the greatest depth where the supply chute 23 and conveyor 14 meet, areas of successive horizontal planes toward the surface of the water indicated at 29 increasing progressively from the greatest depth to the surface.

It will be noted that ripe tomatoes will sink, whereas unripe tomatoes will float. Tomatoes at an intermediate degree of ripeness will float suspended below the surface of the liquid. The supply chute 23 and the conveyor 14 are disposed at the angle relative to each other as described and as indicated in Figure 2, in order to utilize this characteristic of tomatoes in the treatment they receive in the present machine. Ripe tomatoes will sink to the bottom and will be engaged by the conveyor immediately to be transported out of the scalding liquid most rapidly. Unripe tomatoes and those which are only partially ripe will remain floating above the surface of the conveyor bed 16, each tomato that does not float on the surface 29 sinking to a horizontal level predetermined by its degree of ripeness. Thus, tomatoes which float at surface level or float submerged at a horizontal level determined by their degree of ripeness, are transported through the scalding liquid until they come in contact with the conveyor bed 16 to be engaged and lifted by a transverse cleat 17. In this manner the less ripe tomatoes have a greater distance to travel in the scalding liquid, depending upon the horizontal level at which they are suspended, and they travel slowly until they are actuated by the bed 16, thus remaining in the scalding liquid, for a longer period of time, which period of time is governed, and rendered predetermined, by means to be described hereinafter.

The respective sidewalls 24 of the chute and the respective sidewalls 32 which confine the conveyor 14 are spaced apart less than the full width of the container 11, as will be clearly seen in Figures 3, 5 and 6. Spaced inwardly from the

sidewalls 31 of the container are the walls or partitions 32 which demarcate the scalding compartment, there being two compartments in the preferred embodiment shown, to which the heat is applied for bringing the liquid to scalding temperature. These auxiliary compartments 33 are disposed on each side of the material compartment 34 and are narrow to maintain the volume of water contained in them low.

I provide a steam supply system 35 comprising the supply pipe 36, valve controlled, as shown in Figure 3, with pipe lines extending down into the auxiliary compartments and longitudinally thereof at 37. In the steam supply system 35 I provide the temperature controlled inlet 38 which, as indicated, is controlled in accordance with the temperature in the container. I also provide the by-pass 39 which affords a direct line from the steam supply pipe 36 to the outlet pipe 37 which enables me to bring the water to scalding temperature rapidly before placing it under automatic control. This is especially desirable when the apparatus has been idle for a period of time and it is necessary to heat the scalding liquid to a considerable extent.

At 40, I provide a communicating passage through the partition 32 from the auxiliary compartment 33 to the material compartment 34 and at the opposite end of the container I provide another passage 41 through the partition 32 to permit the water to flow from the material compartment 34 back to the auxiliary compartment 33.

The steam supply system 35 functions to heat the liquid to scalding temperature and to maintain it at the desired temperature uniformly. I provide an additional steam inlet 43 at the supply end of the material compartment. This auxiliary steam inlet 43 is for the purpose of inducing circulation of the scalding liquid through the material compartment, and for this purpose a nozzle or jet 44 is provided. Disposed in line with the nozzle is the deflector plate 45 curved as shown in Figure 2 and positioned with its upper edge 46 slightly below the surface of the water. Bolt and slot connections 47, shown clearest in Figure 5, permit the deflector plate 45 to be adjusted vertically. The steam inlet 43 thus functions to induce liquid, which has been heated in the compartment 33, to pass into the material compartment and longitudinally thereof through the supply chute 23 and through the conveyor bed 16. From the end of the material compartment opposite the supply end, the water passes through the passage 41 in the partition 32 back into the auxiliary compartment 33 to complete the circuit. The passages 40 and 41 are constricted as indicated in Figure 2, in order to induce the proper and desired circulation. If the passages are too large the water fails to circulate properly. The passage 40 is constricted to be disposed at a lower level than the curved deflector plate 45 so that the transverse flow of the liquid through the passage 40 does not oppose the flow directed upwardly and longitudinally of the container by the jet 44 and the plate 45.

It will thus be clear that the water between bottom 25 of the supply chute 23 and the bed 16 is constantly flowing in a direction, when viewing Figure 2, towards the right. The valve 48 controls the steam in the steam inlet 43 to regulate the speed of flow of the scalding liquid through the material compartment. It will be readily seen, in viewing Figure 2, that the water

nearest to the surface has a longer distance to travel and, therefore, because the tomatoes float at a horizontal level determined by their degree of ripeness, the tomatoes near the surface will remain in the scalding liquid a longer time.

I have noted that it requires unripe tomatoes a longer time to scald them sufficiently to permit the peelings to be removed readily. It is the purpose of this machine to scald all of the tomatoes, regardless of their degree of ripeness, only so much as is necessary to release the peelings, and render them readily removable. By the use of the machine as herein described, all the tomatoes of a given batch, representing several degrees of ripeness, will receive a degree of treatment necessary to render them uniformly amenable to being pooled. In this manner cooking of the tomato is confined to the surface as much as possible, and the degree of penetration of the cooking is reduced to a minimum. Beyond the extent to which the tomato has been scalded it remains in the raw condition. By the use of my machine I have been able to attain uniform penetration as low as one-eighth of an inch.

To further adjust the degree of scalding of the tomatoes or other material, the container is provided with the overflow pipe 49, adjustable as indicated in dotted lines in Figure 1, to regulate the height at which the scalding liquid is maintained in the material compartment 34 and in the entire container.

The conveyor bed 16 travels from the supply end of the container upwardly and longitudinally toward the deposit station 15 guided in the guideways 50. On its way to the deposit station the bed 16 passes through the chilling compartment 51 enclosed by the transverse walls 52 and 53. The cold water supply enters the compartment 51 through the pipes 54 which are perforated at their sides to direct streams of water against the channel members 55, which cause the water to spray as it falls on the tomatoes resting on the bed 16. The water continues to fall through the conveyor bed 16 into the pan 56 from which it is drained away in the discharge pipe 57. The tomatoes pass from the container, where the peelings have been heated by the scalding liquid, and are suddenly subjected to the cold water supplied in the chilling compartment 51. This causes the peelings to crack, and permits them to be easily removed by the application of a slight amount of pressure to the surface of the tomato.

The invention is not limited to the detailed modification shown and described but is determined by the scope of the accompanying claims.

What I claim is:

1. Scalding comprising a tank, longitudinal upstanding partitions in said tank forming a main compartment and auxiliary compartments, an inclined chute and an inclined conveyor extending into said main compartment from opposite end positions and mutually convergent substantially to form a dihedral angle with its apex substantially at the maximum scalding depth, said chute and conveyor defining with said partitions a scalding chamber, said chute and conveyor being constructed to permit liquid flow therethrough longitudinally of said tank, and steam jet means positioned outside of said scalding chamber between the chute end of said tank and the vertical plane embracing the apex of said angle, for producing a longitudinal flow of liquid through said scalding chamber toward

said conveyor, the openings through said partitions each having ports adjacent opposite ends communicating with the main compartment outside of said scalding chamber providing lateral return circulation through said auxiliary compartments, that part of each partition above the port adjacent the feed end and which defines the upper boundary of said port extending downwardly substantially to the level of the bottom of the scalding chamber.

5 2. Scalding comprising a tank, a longitudinal upstanding partition in said tank forming a main compartment and an auxiliary compartment, an inclined chute and an inclined conveyor extending into said main compartment from opposite end positions and mutually convergent substantially to form a dihedral angle with its apex substantially at the maximum scalding depth, said chute and conveyor defining with the sides of said main compartment a scalding chamber, said chute and conveyor being constructed to permit liquid flow therethrough longitudinally of said tank, and means positioned outside of said scalding chamber between the chute end of said tank and the vertical plane embracing the apex of said angle for producing a longitudinal flow of liquid through said scalding chamber toward said conveyor, the openings through said partition having ports adjacent opposite ends communicating with the main compartment outside of said scalding chamber providing lateral return circulation through said auxiliary compartment, that part of the partition above the port adjacent the feed end and which defines the upper boundary of said port extending downwardly substantially to the level of the bottom of said scalding chamber.

20 3. Scalding comprising a tank, a longitudinal upstanding partition in said tank forming a main compartment and an auxiliary compartment communicating with said main compartment, an inclined chute and an inclined conveyor extending into said main compartment from opposite end positions and mutually convergent substantially to form a dihedral angle with its apex substantially at the maximum scalding depth, said chute and conveyor defining with the sides of said main compartment a scalding chamber, said chute and conveyor being constructed to permit liquid flow therethrough longitudinally of said tank, and steam jet supplying and directing means positioned outside of said scalding chamber between the chute end of said tank and the vertical plane embracing the apex of said angle, for producing a longitudinal flow of liquid through said scalding chamber toward said conveyor, communication of said auxiliary compartment with said main compartment being limited to ports in said partition adjacent opposite ends communicating with the main compartment outside of said scalding chamber providing lateral return circulation through said auxiliary compartment, that port adjacent the chute end being restricted to the lower part of said partition.

25 4. Scalding comprising a tank, a longitudinal upstanding partition in said tank forming a main compartment and an auxiliary compartment, an inclined chute and an inclined conveyor extending into said main compartment from opposite end positions and mutually convergent substantially to form a dihedral angle with its apex substantially at the maximum scalding depth, said chute and conveyor defining with the sides of said main compartment a

scalding chamber, said chute and conveyor being constructed to permit liquid flow therethrough longitudinally of said tank, steam jet supplying and directing means positioned outside of said scalding chamber between the chute end of said tank and the vertical plane embracing the apex of said angle for producing a longitudinal flow of liquid through said chute, scalding chamber and conveyor, that part of said partition which extends below the level of the bottom of the scalding chamber having ports adjacent its opposite ends establishing communication between said main and auxiliary compartments outside of said scalding chamber providing lateral return circulation through said auxiliary compartment, that port which is adjacent the chute end of said tank extending forwardly of the transverse vertical plane through the steam jet means, said partition above the level of the bottom of said scalding chamber being imperforate in that portion which extends from a vertical transverse plane through the apex of said dihedral angle, at least to the vertical transverse plane passing through said steam jet means.

5. Scalding comprising a tank, a longitudinal upstanding partition in said tank forming a main compartment and an auxiliary compartment, an inclined chute and an inclined conveyor extending into said main compartment from opposite end positions and mutually con-

vergent substantially to form a dihedral angle with its apex substantially at the maximum scalding depts, said chute and conveyor defining with the sides of said main compartment a
10 scalding chamber, said chute and conveyor being constructed to permit liquid flow therethrough longitudinally of said tank, steam jet supplying and directing means positioned outside of said scalding chamber between the chute end of said tank and the vertical plane embracing the apex of said angle for producing a longitudinal flow of liquid through said chute, scalding chamber and conveyor, that part of said partition which extends below the level of the bottom of the
15 scalding chamber having ports adjacent its opposite ends establishing communication between said main and auxiliary compartments outside of said scalding chamber providing lateral return circulation through said auxiliary compartment, that port which is adjacent the chute end of said tank extending forwardly of the transverse vertical plane through the steam jet means, said partition above the level of the bottom of said scalding chamber being imperforate in that portion which extends from a vertical transverse plane through the apex of said dihedral angle, at least to the vertical transverse plane passing through said steam jet means.

30

RAYMOND L. HAYNIE.
